US00D769626S

(12) **United States Design Patent** (10) **Patent No.:** **US D769,626 S**
Bloch et al. (45) **Date of Patent:** **** Oct. 25, 2016**

(54) **REFILL HEAD FOR ELECTRIC
TOOTHBRUSH**

(71) Applicant: **COLGATE-PALMOLIVE
COMPANY**, Piscataway, NJ (US)

(72) Inventors: **Brian Bloch**, Hillsborough, NJ (US);
Lars Ralf Rainer Lieberwirth,
Glashuetten (DE)

(73) Assignee: **COLGATE-PALMOLIVE
COMPANY**, New York, NY (US)

(**) Term: **14 Years**

(21) Appl. No.: **29/477,154**

(22) Filed: **Dec. 19, 2013**

(51) **LOC (10) Cl. 04-02**

(52) **U.S. Cl. D4/101**

Primary Examiner — Karen E Eldridge Powers

(57) **CLAIM**

The ornamental design for a refill head for electric toothbrush, as shown and described.

DESCRIPTION

FIG. 1 is a front perspective view of the new design; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

All broken lines shown in the drawings illustrate environmental structure and form no part of the claimed design.

1 Claim, 4 Drawing Sheets
